UNITED STATES PATENT OFFICE.

JOHN CLIFFORD YOUNG, OF PITTSBURGH, PENNSYLVANIA.

NECKTIE HOLDER.

Application filed September 8, 1927. Serial No. 218,318.

The invention relates to a necktie holder.

The object of the present invention is to improve the construction of necktie holders and to provide a simple, practical and efficient necktie holder of strong, durable, and comparatively inexpensive construction, adapted to be readily applied to a necktie and a shirt and connecting the necktie with the garment and capable of allowing a limited movement 10 of the necktie up and down so that the necktie will not be dislodged when the wearer lifts his chin or moves his head, as is often the case where a single clasp is employed for securing the necktie to the shirt.

15 When the ordinary clasp is employed for securing the necktie to the shirt, and the necktie is left loose above the clasp, the necktie sags over the clasp and becomes wrinkled and unsightly, and when there is no slack in the 20 necktie above the clasp the knotted portion of the necktie is often dislodged and moved from its proper position when the wearer lifts his chin. The present invention is designed to avoid these objections resulting from the 25 use of the ordinary necktie clasp.

With these and other objects in view, the invention consists in the construction and novel combination and arrangement of parts hereinafter described, set forth in the claims 30 appended hereto, and illustrated in the accompanying drawings, it being understood that various changes in the form, size and minor details of construction, within the scope of the claims, may be resorted to without departing from the spirit of the invention 35 or sacrificing any of the advantages thereof.

In the drawing:

Figure 1 is a front elevation of a necktie holder constructed in accordance with this invention and shown applied to a necktie, a portion of a shirt being shown and a necktie being illustrated in dotted lines.

40 Fig. 2 is a side elevation of the necktie holder showing the loop member arranged on the lower member of the holder, the device being detached.

45 Fig. 3 is a similar view, the loop member being removed from the lower member of the holder.

50 Fig. 4 is a plan view illustrating another form of loop member.

In the accompanying drawing, in which are illustrated the preferred embodiments of

the invention, the necktie holder comprises in its construction a clasp 1, a short chain 2 or 55 other suitable flexible connection, and a loop member which, in the form illustrated in Figs. 1 to 3, inclusive, consists of an oblong loop 3 composed of spaced sides and connecting ends and adapted to be arranged on the 60 clasp 1, as clearly illustrated in Fig. 2 of the drawing. The clasp 1 may be of any desired construction and is composed of upper and lower members 4 and 5 hinged together adjacent their rear ends by a suitable pintle 6 65 and yieldably urged towards each other by a suitable spring 7. One end of the chain is suitably secured to the lower clasp member and the loop member, which is secured to the other end of the chain, is adapted to be placed 70 on the upper or lower clasp member. The clasp members are provided at their front ends with inwardly extending teeth or engaging portions 8 for gripping the necktie in the usual manner. In the form illustrated 75 in Figs. 1 to 3, inclusive, of the drawings, the chain is passed through the adjacent button-hole 9 of the shirt 10 and the loop member is placed on the lower or rear clasp member or jaw and the clasp is then engaged with the 80 edge of the necktie. The chain permits a limited movement of the necktie and retains the same in place without subjecting the necktie to a constant strain which often results in a 85 dislodgement or displacement of the knotted portion of a necktie when the same is subjected to a constant tension with an ordinary clasp.

In Fig. 4 of the accompanying drawing is illustrated another form of loop member 11, 90 having a narrow portion 12 and an enlarged portion 13 forming a substantially keyhole opening. The loop member 11 is designed to be engaged with a button 14 of a shirt, but it may also be placed on the clasp if desired. 95 Various other forms of loop members may, of course, be employed.

What is claimed is:

1. A necktie holder comprising a necktie engaging clasp, a loop member, and a flexible 100 connection having one end attached to the clasp and the other end attached to the loop member, said loop member being of substantially oblong form and of a size to fit on one of the members of the clasp after being 105 passed through a buttonhole of a shirt, where-

by the flexible connection will form a loose connection for anchoring the necktie to the shirt.

2. A necktie holder comprising a necktie engaging clasp adapted to engage the side edge of the tie, a rigid loop member, an inelastic flexible connection between the clasp and the loop, the said connection being of

such a length as to allow of small relative movement between the tie and the shirt of the wearer without placing the connection under tension.

In testimony whereof I have hereunto set my hand.

JOHN CLIFFORD YOUNG.
